[57] CLAIM

The ornamental design for an umbrella clamp mounting bracket, as shown and described.

DESCRIPTION

FIG. 1 is a perspective view of an umbrella clamp mounting bracket showing my new design;

FIG. 2 is a front elevational view thereof;

FIG. 3 is a top plan view thereof;

FIG. 4 is a bottom plan view thereof;

FIG. 5 is a left end view thereof;

FIG. 6 is a right end view thereof; and

FIG. 7 is a rear elevational view thereof.

The broken line illustration in FIG. 1 depicts the manner of using the invention.
